UNITED STATES PATENT OFFICE

CARL W. LINDGREN, OF LOS ANGELES, CALIFORNIA

CLOTHES HANGER

Application filed June 11, 1930. Serial No. 460,446.

This invention relates to improvements in clothes hangers.

An object of the invention is to provide an improved clothes hanger which is of simple and durable construction on which a garment, such as a pair of trousers, may be easily mounted and held properly in such position as well as be conducive to preserve creases formed in pressing.

10 Another object of the invention is to provide a clothes hanger having a transverse bar, which bar may be the body of a clothes hanger itself or a part thereof and which has two sleeves slidably mounted on the bar, 15 each having a garment engaging means so that a garment may be suspended therebetween, the sliding ability of the sleeves enabling the device to be adjusted to variously sized garments and also being such that when 20 the garment is suspended by the clothes hanger the sleeves will bind on the bar, keeping the garment taut in the desired position.

Another object of the invention is to provide a device which can be easily applied to 25 bar hangers now in general use, enabling such bar hangers to be converted into clothes hangers of the improved construction.

With the foregoing and other objects in view, which will be made manifest in the following detailed description, and specifically pointed out in the appended claims, reference is had to the accompanying drawings for an illustrative embodiment of the invention, wherein:

35 Fig. 1 is a front view in elevation of the improved clothes hanger illustrating a pair of trousers as having been mounted thereon.

Fig. 2 is a side elevation of one of the sleeves with its garment engaging means.

40 Fig. 3 is a top plan view of the same.

Fig. 4 is a side elevation of a construction adapted to be applied to bar hangers now in general use to convert them into clothes hangers of the improved construction.

45 Fig. 5 is a top plan view of the construction illustrated in Figure 4.

Fig. 6 is a perspective view of a part of the construction illustrated in Figures 4 and 5.

50 Referring to the accompanying drawings, wherein similar reference characters design-

nate similar parts throughout, the body of the clothes hanger is generally designated at 10, having a central suspending hook 11, and being preferably so formed as to be form fitting and properly suspend a gentleman's 55 coat. The ends of the body 10 are connected by a transverse bar 12, preferably cylindrical in form but which may be of other shapes. On the transverse bar 12 there are slidable sleeves 13 and 14. Each sleeve has secured 60 thereto two sections of wire, indicated at 15 and 16, the outer ends of which are bent downwardly as at 17 forming laterally spaced hooks 18; the crotches of which, indicated at 19, open outwardly and upwardly. The laterally spaced hooks 18 are arranged, as shown in Figure 1, on the outer ends of their respective sleeves. These hooks are adapted to engage upon the garment G and may be inserted 65 through the belt loops L or on suspender 70 buttons B.

In applying a garment G to the clothes hanger the belt loops L are slipped onto the hooks 18 or the buttons B may be positioned in the crotches 19 depending on whether both 75 the belt loops L and buttons B are present and, if so, which is nearest the top of the crease in the trousers produced by pressing. When the garment has thus been applied to the hooks 18, the sleeves 13 and 14 are 80 forced outwardly on the transverse bar 12, thus stretching the garment G taut between them. When they are released by virtue of the fact that the hooks are arranged on the outer ends of the sleeves and suspend the 85 weight of the garment, the sleeves 13 and 14 bind on the transverse bar 12, thus preventing the inward movement of the sleeves. In this manner the garment G is held in the proper position to preserve the creases in 90 the trousers. The garment is nicely suspended and a coat and/or a vest may be subsequently applied to the body 10. When it is desired to remove the garment G from the clothes hanger a slight manual manipulation 95 of the sleeves 13 and 14 will disturb their binding action so that they can freely slide on the bar 12 toward each other, facilitating removal of the garment G from the hooks.

In Figures 4, 5 and 6, there is illustrated a 100

slightly modified form designed to convert bar hangers already in general use into clothes hangers of the improved construction. To this end the construction in Figures 4, 5, and 6, comprises a section of sheet metal 20 rolled into cylindrical form and having its opposed edges provided with knuckles 21 and 22. These knuckles are adapted to be moved into alignment with each other to receive the shank 23 of the garment engaging means. In this construction the garment engaging means may be formed of a single section of wire reversely bent upon itself at about its center to provide the shank 23 and having its outer ends bent downwardly as at 24 to provide the laterally spaced upwardly and outwardly open hooks 25. In applying this construction to the bar 12 of a bar hanger, the sheet metal section is sprung open sufficiently to permit it to be slipped onto the bar. Thereafter it is contracted about the bar until the knuckles 21 and 22 are in alignment. The shank 23 is then inserted, thus fastening the opposed edges of the sheet metal section to each other about the bar and simultaneously mounting the hooks 25 on the sheet metal section which forms the sleeve. The operation of this form of construction is identical with that previously described in connection with the construction illustrated in Figures 1 to 3 inclusive.

From the above described constructions it will be appreciated that a novel, simple and advantageous, clothes hanger is provided, which is of simple and durable construction, enables a garment to be easily and quickly applied thereto or removed, and which serves to suspend the garment in such a position as to be conducive to preserve its press. Various changes may be made in the details of construction without departing from the spirit or scope of the invention as defined by the appended claims.

I claim:

- 15 1. A garment hanger comprising a transverse bar, a sleeve split along one side and having its opposed edges provided with knuckles capable of being positioned in alignment, and garment engaging means having a shank extending through the knuckles.
- 20 2. In a garment hanger, a section of sheet metal rolled into cylindrical form and having its opposed edges provided with knuckles capable of being positioned in alignment, and garment engaging means having a shank extending through the knuckles.

In testimony whereof I have signed my name to this specification.

CARL W. LINDGREN.
